UNITED STATES PATENT OFFICE

2,470,605

ELECTRIC DISCHARGE DEVICE WITH
INTERNAL CAPACITOR

Harold R. Cummings, Schenectady, N. Y., assignor
to General Electric Company, a corporation of
New York

Application February 14, 1947, Serial No. 728,553

4 Claims. (Cl. 250—27.5)

1

My invention relates to electric discharge devices particularly of the transmitting type.

In the operation of electric discharge devices, it is often desirable that the control grid be shielded from the anode. Also, at higher operating frequencies, it is desirable to connect the screen grid with the cathode through a capacitor to maintain these electrodes at the same high frequency voltage. In accordance with an important aspect of my invention, I provide an improved capacitor construction within an electric discharge device which connects the screen grid and cathode together with respect to high frequency voltages. The improved structure also provides a support for the screen grid and a shield completely shielding the control grid from the anode.

It is an object of my invention to provide a new and improved electric discharge device.

It is another object of my invention to provide a new and improved capacitor construction in combination with the electrodes of an electric discharge device.

It is a still further object of my invention to provide a compact and rugged electric discharge device having a capacitor incorporated within the envelope and connected between the screen grid and cathode of the device.

My invention will be better understood by reference to the following description taken in connection with the accompanying drawing, and its scope will be pointed out in the appended claims. In the drawing, Fig. 1 is an elevational view in section of an electric discharge device embodying my invention; Fig. 2 is a sectional view taken along the line 2—2 of Fig. 1; Fig. 3 is a sectional view taken along the line 3—3 of Fig. 1, and Fig. 4 is a sectional view of the capacitor construction taken along the line 4—4 of Fig. 2.

Referring now to the drawing, I have shown my invention embodied in a transmitting type of electric discharge device including a generally cylindrical glass envelope 1, closed at its lower end by a dish-shaped header 2 through which are sealed a plurality of lead-in conductors 3—7 inclusive. As illustrated, each lead-in conductor is bonded to a surrounding sleeve 8, which is sealed at one end to the glass header 2.

The anode 9 of the device is bell-shaped and is supported from the opposite end of the envelope by a supporting stud 10 connected at one end with the closed end of the anode and bonded at the other end to an inverted cup-shaped terminal 11, which is sealed at its lower edge to a flange 12 formed on the envelope wall.

2

The particular embodiment of my invention illustrated is a tetrode and includes in addition to the anode 9, a screen or number two grid 13, a control grid 14, and a double helical filament 15 including a central supporting post 16. These elements are supported in concentric and coaxial relation within the anode 9.

The end terminals of the cathode are connected with lead-in conductors 3 and 4 by conductors 17 and 18 of smaller diameter. The center post 16 is supported at its lower end by a circular disk 19 of insulating material which is, in turn, supported on shoulders provided on lead-in conductors 3, 4, and 7. The shoulders are provided at 10 the junction of the lead-in conductors 3 and 4 for example, and the shoulder conductors 17 and 18. The center post 16 terminates in a bolt 20, which extends through a central aperture at the disk 19 where it is secured by a nut 21. The control grid 14 includes a plurality of U-shaped elements which are bonded at their lower ends to a cylindrical sleeve 22. These elements may be secured together at the cross-over points, by welding to a washer or, as illustrated, by means of a 15 hollow rivet 23. The grid assembly thus formed is supported from lead-in conductors 5 and 6 by conductors 24 and 25. The screen grid 13 is of generally similar construction and the individual elements are joined together at their cross-over 20 points by welding to a washer 26. At the lower end the grid elements are bonded to a flanged collar 27 which, in assembly, is joined to a similar collar 28 carried by an apertured shield and supporting member 29. The member 29 is formed of 25 conducting material and is supported from the insulating disk 19 by means of a cylindrical metal member 30 having an inturned flange 30' at its upper end. The lower edge of the member 30 rests on the disk 19 and provides the support for 30 the screen grid assembly. This member also provides one plate of a capacitor assembly which is completed by a second cylindrical shield member 31 connected with the screen grid supporting member 29 and by a third cylindrical member 32. 35 The member 32 is provided with an inwardly directed flange 33 at its lower end which is secured to the disk 19 by rivets 34. An electrical connection between the central post of the cathode and the member 32 is provided by a conducting strap 35 which terminates in a conical terminal 36. The terminal 36 is secured by the nut 21 which secures the central post 16 to the supporting disk 19. The marginal portion of the member 29 and the inwardly directed flanges on the capacitor elements 30 and 31 are bonded together as by welding. As

illustrated, member 31 is provided with a circumferential rib 37 which extends upwardly toward the anode of the device, functioning to minimize the escape of the electrons from inter-electrode space. Elements 31 and 32 are maintained in spaced relation by insulating members 38 which are received in suitable slots formed in the intermediate capacitor element 32. As illustrated, these spacers are slotted on the sides to receive the edges of the member 32 defining the recesses and in this way to determine positively the spacing between the capacitive elements 30, 31, and 32.

The disk 19 of insulating material is firmly held against the shoulders provided by the lead-in conductors 3, 4, and 7 by means of sleeves 39 bonded to conductors 17 and 18 which extend from lead-in conductors 3 and 4 and to a conductor 40 which is connected with lead-in conductor 7 and which extends through the member 29 and is secured thereto by a sleeve 41. It will be apparent that lead-in conductor 7 provides an externally accessible connection with the screen assembly as well as a means for securing the capacitor assembly together. The assembly is further secured by a rivet 42 which extends through the assembly and is provided with sleeves 43 and 44 bearing respectively on the insulating disk 19 and the member 29.

From the foregoing detailed description it will be apparent that my invention provides an improved assembly which incorporates a bypass capacitor within the tube envelope and between the screen grid and cathode. It is apparent that many of the structural features may be employed regardless of the electrodes to which the capacitor is connected. At the same time, the structure provides a shield between the anode and control grid which is shaped to minimize the escape of electrons from the inter-electrode space. This structure combines the shielding and capacity providing functions and, at the same time, provides a compact and rigid supporting structure for the various elements of the device. The means for supporting the screen grid including the collars 27 and 28 facilitate lining up of the individual elements of the control and screen grid structures during assembly. It is apparent that after the control grid is assembled on the header, that the screen grid assembly may be placed in position with the extending flanges of collars 27 and 28 in contact and the screen grid rotated until the individual elements are in line with the elements of the control grid. The flanges are then welded together.

While I have described and illustrated a particular embodiment of my invention, it will be obvious to those skilled in the art that changes and modifications may be made without departing from my invention in its broader aspects and I therefore, aim in the appended claims to cover all such changes and modifications as fall within the true spirit and scope of my invention.

What I claim as new and desire to secure by Letters Patent of the United States is:

1. An electric discharge device including an envelope, a plurality of conductors sealed through

said envelope, a generally planar body of insulating material supported from said conductors, a pair of cylindrical conducting members supported from said insulated member in closely spaced relation and providing the plates of a capacitor, one of said conducting members having an inwardly directed flange, and a grid supported from said flange.

2. An electric discharge device comprising an envelope, a cathode, a control grid, a screen grid, and an anode supported within said envelope in concentric relation, a plurality of lead-in conductors sealed through said envelope, an insulating support carried by said lead-in conductors, 10 a generally cylindrical conducting member secured to said support and to said screen grid, a second cylindrical conducting member connected with said cathode and supported by said insulating support, said second conducting member extending in spaced and insulating relation with respect to said first cylindrical member, and conducting means extending from certain of said lead-in conductors to said control grid, said conductor means being shielded from said anode by said generally cylindrical conducting member.

3. An electric discharge device comprising an envelope, a cathode, a control grid, a screen grid, and an anode supported within said envelope in concentric relation, a plurality of lead-in conductors sealed through said envelope, an insulating support carried by said lead-in conductors, a generally cylindrical conducting member secured to said support and to said screen grid, a second cylindrical conducting member connected with said cathode and supported by said insulating support, said second conducting member extending in spaced and insulating relation with respect to said first cylindrical member and co-operating therewith to provide a capacitor.

4. An electric discharge device comprising an envelope, an anode, a grid electrode, and a filamentary cathode mounted in concentric relation in the order named within said envelope, said cathode being of the filamentary type and including a pair of end terminals and a central terminal, a plurality of lead-in conductors sealed through said envelope and including a pair of conductors connected with the end terminals of said cathode, an insulating member supported from said pair of lead-in conductors, a pair of conducting members of extended area secured to said insulating member in spaced and insulated relation providing a capacitor means connecting the central terminal of said cathode with one of said members and means supporting said grid electrode from the other of said members.

HAROLD R. CUMMINGS.
